United States Patent Office

Des. 176,118
Patented Nov. 22, 1955

176,118

CHILD'S DESK

Jon W. Hauser, St. Charles, Ill., assignor to Hawley Products Company, St. Charles, Ill., a corporation of Delaware

Application March 7, 1955, Serial No. 34,875

Term of patent 14 years

FIG. 1

(Cl. D33—11)

FIG. 3

Fig. 1 is a front elevational view of a child's desk, embodying my new design;

Fig. 2 is a side elevational view thereof; and

Fig. 3 is a top plan view thereof.

I claim:

The ornamental design for a child's desk, as shown.
